BURNER SAFETY CONTROL

Oscar L. Bock, Madison Wis., assignor to Bock
Oil Burner Corporation, Madison, Wis., a
corporation of Wisconsin

Application July 2, 1934, Serial No. 733,360

1 Claim. (Cl. 137—68)

The present device relates in general to a device for supplying fuel oil to oil burners, and more particularly to a device for controlling the flow of fuel oil to an oil burner. More specifically the 5 invention relates to a device for controlling the flow of oil to the burner so as to assure safety from flooding or overflowing both under normal and abnormal conditions.

The primary object of the present invention is 10 to provide a new and improved device for supplying fuel oil to burners and controlling the flow of the oil to the burners, and which is provided with new and novel means for removing or draining the surplus oil, which is safe and foolproof, 15 and which is so constructed and arranged so that the device will operate positively and efficiently.

Another object of the invention is to provide 20 improved means for controlling the flow and overflow of oil to the burner by providing a sump in which certain mechanism is controlled by the oil level therein and which is so constructed and arranged that the customary or conventional exposed overflow drip buckets to operate shut-off means may be eliminated.

A still further object of the invention is to 25 provide a new and novel control device, which is provided with means for controlling the supply of fuel to the oil burner, which is provided with new and novel cut-out means, which has means for collecting the overflow as well as providing shut-off means, and which is constructed and arranged 30 to permit for the reception of excess fuel supplied to the burner as well as providing means for draining the device either by the removal of a sump or by the operation of a conveniently located and efficiently operated valve, depending 35 upon whether or not the sump is to be connected by a return line from the burner.

Numerous other objects and advantages will be 40 apparent throughout the progress of the following specification.

The accompanying drawing illustrates a selected embodiment of the invention and the view shown therein is a detail sectional elevation 45 through a device and burner showing the various parts in a practical arrangement.

The specific arrangement and construction 50 herein shown, for the purpose of illustration, comprises a fuel supply tank 1 containing a hydrocarbon such as fuel oil which feeds through a supply pipe 2 through a strainer 3 operatively arranged in a supporting housing 4. A connecting nipple 5 connects the inlet and strainer housing 4 to the chamber housing 6. Fuel oil from the 55 supply source 1 passes through the feed line 2

into the housing 4 where it is strained by the strainer 3 and then passes through the nipple 5 and through the restricted opening 7 formed in the supporting or coupling member 8. This latter member 8 is provided with a longitudinal or vertical bore 9 into which there is arranged for operation a valve 10. Ports 11 communicate with the opening 7 to supply oil to the chamber within the chamber housing 6. The oil level rises in the chamber and raises the float 12 which, when rising, causes the needle valve 10 to be seated against the inlet opening 7 and shut off further fuel supply. After sufficient fuel oil is drawn off from the chamber, the float 12 will again lower and cause the needle valve to again become unseated 15 and permit further supply of fuel oil. The oil flows out of the chamber outlet 13 and through the burner feed line 14 to the burner 15. A metering device 16, either manually or electrically controlled, (electrical control being shown) may 20 be interposed in the line 14 as shown in the drawing. The oil coming through the line 14 is fed to the burner bowl where it flows to the lower surface and is burned. In case of flame failure or extinguishment, the level of the oil in the bowl 25 will rise to the lower row of holes 17 in the fire pot 18 where it will flow into the outer bowl 15 and then through the return line 19 to the sump 20.

As previously mentioned, the valve 10 is controlled by the float 12 so as to maintain a constant level of oil in the chamber 6. As the oil level rises in the chamber, raising the float 12, the needle valve 10 will be depressed due to the action of the float 12 engaging the hinged lever 35 arm 21. The hinged lever arm 21 is pivoted at 22 and has its free outer end 23 operatively connected to a part 24 on the valve 10 to positively raise and lower the needle valve in conformance 40 with the movement of the float 12 and maintaining a normal constant level within the chamber 6. However, in case of faulty operation and should the level of the oil in the chamber rise, it will flow over a spillway 25 into the lower sump 20. As the oil continues to rise in the sump 20, due to the 45 overflow of the chamber 6, a float 26 arranged in the sump 20 will rise. An arm 27 fastened to the float 26 is pivotally connected to a transverse rod or lever 28 as indicated at 29. This transverse lever 28 is pivotally mounted as indicated at 30. 50 As the fuel level in the sump 20 raises the float 26, the arm 27 and the lever 28 will be operated and unhook the dog 31 from its engaging arm 32 which is pivoted at 33. A spring 34 normally urges the engaging arm 32 in a downward direc- 55

tion and normally holds the dog into engaged position with the arm 32. When the float 26 rises to swing the lever 28 on its pivot 30, the dog 31 will become disengaged and the spring 34 will cause the needle valve 10 to be depressed against its seat 7 and thereby shut off the feed of fuel to the chamber 6.

To again put the device in operation, the oil must be drained from the sump 20 so that the float 26 will fall to a lower position and allow the engaging arm to be reset and again take the weight of the spring 34 off of the needle valve 10. This latter operation is done by pulling down on the valve pin 35 to compress the spring 36 to unseat the needle valve 37 from its seat 38 and permit the oil to pass from the sump through the orifice or drain opening 39. The oil will then flow out of the sump through the needle valve opening 39 which is drilled in the valve body 40. When the pin or needle valve 35 is released, the spring 36 will drive the needle valve 37 against its seat preventing further discharge of oil until the stem 35 is again pulled downwardly. When the oil is drained as low as possible through this latter described means, a small amount of the fuel will remain in the burner outlet 19 and in the trap connection designated generally by the numeral 41. The burner drain 19 and the connection 41 act to prevent air and gases from being blown back into the control device when the burner is operating and where pressure is around the inner burner bowl as would be the case when a motor driven blower is attached to the outer burner housing 15. It is apparent that gases might be forced back from the bowl 18 through the connecting pipe 19 into the sump 20 and escape into the room if it were not for the liquid seal between the burner and the device, the liquid seal being the fuel oil in the trap 41 and the pipe line 19.

In some cases it might be expedient, convenient or more economical to dispense with the valve 35 and the return line 19. If such is the case, the sump 20 can be made removable by providing a hanger pin 42 which engages a part of the sump and a lug 43 and a locking connection 44. This locking connection may comprise a spring arm 45 fastened to a part of the device as indicated at 46, and a lip 47 formed on the sump, the lip 47 being engaged by a keeper end 48 on the spring arm 45. Therefore, when the sump is filled with fuel a sufficient distance to prevent the reception of oil to the chamber 6, the sump can very conveniently be removed and the contents poured therefrom.

Regardless of the sump connection and arrangement, the device is of such a construction that the oil cannot escape from the sump at least until the mechanism has tripped and shut off further flow of oil.

The invention provides new and novel means for positively cutting off the fuel supply line

when a certain amount of excess fuel has been delivered through faulty operation or otherwise. The parts are simple and compact in construction and arrangement and the device as a whole operates positively and efficiently. The invention further provides for a return line to the sump or for a removable sump where no return line is required or desired. In cases where the return line is used, and it is deemed advantageous to use it, the sump may be provided with a spring valve operated so that it will always be free. The particular construction of the sump outlet valve is such that the valve cannot be blocked up by placing objects underneath it as it must be pulled outwardly to drain the sump. Also the arrangement of the valve is such that it cannot be left open accidentally. Valve mechanism designated generally by the numeral 49 may be provided for shutting off the communication of fuel from the chamber 6 to the burner feed line 14.

Changes may be made in the form, construction, and arrangement of the parts without departing from the spirit of the invention or sacrificing any of its advantages, and the right is hereby reserved to make all such changes as fairly fall within the scope of the following claim.

The invention is hereby claimed as follows:

A liquid control mechanism comprising an intake chamber, a control chamber and a sump chamber, said intake chamber and said sump chamber being in parallel juxtaposition and located directly below the control chamber, a vertical passage connecting the top of the intake chamber to the bottom of the control chamber, a valve seat disposed at the opening in the control chamber of the said vertical passage, a valve closure rod operatively mounted in the valve seat and adapted to move longitudinally in a vertical line into and out of engagement with the valve seat, a collar on said valve closure rod, a yoke pivotally mounted in the control chamber, one end of said yoke engaging the collar, a float member rigidly mounted on the other end of the yoke means, outlet means in the control chamber, auxiliary spring actuated means adapted to operatively engage the valve closure rod and move the same to closed position, means normally holding said auxiliary means out of operative engagement with said valve closure rod, conduit means opening into the top of the sump chamber, said conduit means opening into the control chamber at a predetermined level above the level of the outlet means of the control chamber, sump float means in the sump chamber, and means operatively connecting the sump float means with the said holding means, said connecting means being operable to actuate the auxiliary means into operative engagement with respect to the valve closure rod to move the same to closed position when the sump float means rises in the sump to a predetermined level.

OSCAR L. BOCK.
